UNITED STATES PATENT OFFICE

LE ROY O. BROWN, OF CHICAGO, ILLINOIS, ASSIGNOR TO JUSTRITE MANUFACTURING COMPANY, OF CHICAGO, ILLINOIS, A CORPORATION OF ILLINOIS

DESIGN FOR A LAMP

Application filed April 7, 1930. Serial No. 35,182. Term of patent 14 years.

To all whom it may concern:

Be it known that I, LE ROY O. BROWN, a citizen of the United States, residing at Chicago, county of Cook, State of Illinois, have invented a new, original, and ornamental Design for a Lamp, of which the following is a specification, reference being had to the accompanying drawing, forming a part hereof.

The figure is a perspective view of the lamp showing my new design, the opposite side of the lamp having substantially the same appearance as the side shown in the figure.

I claim:

The ornamental design for a lamp as shown and described.

LE ROY O. BROWN.
